14 Claims. (Cl. 102—83)

This invention relates to acceleration responsive arming devices for use in fusing systems for missile carried explosives, and more particularly to acceleration responsive arming devices of the type which remain unarmed until lapse of a definite interval of time after initial acceleration.

The object of the present invention is to provide an improved device of the type referred to, which may be selectively preset to remain unarmed for any one of several intervals of time.

Other objects and many of the attendant advantages of this invention will be readily appreciated as the same becomes better understood by reference to the following detailed description when considered in connection with the accompanying drawings wherein:

FIG. 1 is a side elevation of the device of the present invention;

FIG. 1A is a fragment of a side elevation like FIG. 1, illustrating a particular adaptation of the device of FIG. 1;

FIG. 2 is an end view of the device of FIG. 1;

FIG. 2A is an end view of the device of FIG. 1A;

FIG. 3 is a plan view of the device of FIG. 1;

FIG. 4 is a section taken along line 4—4, FIG. 3, showing the device in the unarmed position and diagrammatically showing certain elements of an exemplary fuse system in which the device may be employed;

FIG. 4A is a section like FIG. 4 showing the device in its armed position;

FIG. 5 is a section taken along line 5—5, FIG. 4;

FIG. 6 is a detail indicated by arrow 6, FIG. 4;

FIG. 7 is an enlarged section taken along line 7—7, FIG. 3;

FIG. 8 is a section taken along line 8—8, FIG. 7;

FIG. 9 is a section taken along line 9—9, FIG. 7; and

FIG. 10 is an exploded view of a detail indicated by arrow 10, FIG. 2.

Referring in detail to the drawing, the invention comprises an arming and firing unit 20, indicated as a whole in FIG. 1, which unit may be employed in various fuse systems for missile carried explosive charges, as, for example, the arrangement shown in FIG. 4 which includes an electrical actuator 22 for providing an electrical command signal suitable for igniting an electrical primer, a booster charge 24, and a main charge 26, the other components of the fuse system being omitted since they are not important to the present invention.

Within unit 20, a hollow shaft 28, FIG. 7, having a central bore 30 extending between its ends is rotatably mounted to a housing 32 by ball bearings 34, 36. A shaft 38 is journaled in bore 30 with its ends projecting from the respective ends of shaft 28. A disk shaped flange 40 is formed on one end of shaft 28 and a matching disk shaped flange 42 is fixed to the adjacent end of shaft 28. As best shown in FIG. 10, flange 40 has a single threaded aperture 48 formed therein and flange 42 has a series of apertures 50, 50, each registerable with aperture 48 in a different predetermined angular position of shaft 38 relative to shaft 28. A hub 44 is formed on flange 42 having a slot 46 formed therein adapted to be engageable with a suitable hand tool, such as a screw driver, to permit a desired manual adjustment of the

2

angular position of shaft 38 to any one of the aforesaid angular positions, the significance of such adjustment to become hereinafter apparent. After such adjustment, a screw 52 is extended through one of the series of apertures 50, 50 and into aperture 48, securing shafts 28 and 38 together for joint rotation. A spiral wound flat spring 54, FIG. 8, disposed in a cavity 56 formed in housing 32 resiliently urges the shafts to rotate in the direction of arrow A, one of its ends being fixed to shaft 28 and the other fixed to housing 32. The shafts are drivingly connected to a conventional oscillating pallet type escapement mechanism 58, selected to cause the shafts to rotate at a predetermined constant rate of rotation, through a spur gear 60 fixed to shaft 28, which gear enmeshes a first pinion 62 of the escapement mechanism. The aforesaid arrangement of spring 54 and escapement mechanism 58 constitute a clockmotor which biases the shafts to rotate at a constant rate of rotation in the direction of arrow A, FIG. 1.

A cavity 64, FIG. 1, having opposite walls 66, 68 is formed in housing 32. An interlock element 70, FIG. 9, is fixed to shaft 28. When shafts 28 and 38 rotate, interlock element 70 describes an arc of rotation represented by arrow 72, which arc of rotation in part extends into cavity 64. A rod 74, FIG. 1, suitably fixed at its ends to the housing, extends between walls 66 and 68, and a weight 76 is slideably mounted on rod 74 for rectilinear motion, the rod slideably extending through a bore 78 extending through the weight. The weight is further supported for such movement by a pin 80, FIG. 7, carried thereby, which rides in a groove 82 formed in the housing. A helical compression spring 84, FIG. 1, is mounted about rod 74 between weight 76 and wall 68, resiliently urging weight 76 toward wall 66 to the initial limit stop position shown, against wall 66. A step 86, FIG. 9, formed on weight 76 has a path of movement which in part coincides with the arc of rotation of interlock element 70. The mechanism is so arranged that when weight 76 is in its initial position, step 86 initially engages interlock element 70 locking shafts 28 and 38 against the urge of spring 54, establishing an initial angular position of the shafts. Until the shafts have rotated from their initial position through an angle in excess of angle θ , step 86 may engage interlock element 70.

A rotor 88, FIG. 4, having formed thereon a first collar 90, a stud 92, a second collar 94, and a cam 96 is rotatably mounted to housing 32, stud 92 being disposed in a cavity 98, FIG. 3, formed in the housing and second collar 94 being journaled in a bore 100 also formed in the housing. A disk 102 fixed to shaft 38 in a predetermined angular position and having a transverse slot 104 formed therein is generally disposed in cavity 98 for cooperation with stud 92. A torsion spring 106 mounted about rotor 88, resiliently urges rotor 88 to rotate in the direction of arrow B, FIG. 2, one end of the spring engaging a slot 108, FIG. 6, formed in surface 110 of the housing, and the other end extending into an aperture 111 formed in collar 90 of the rotor, the spring being retained in place by means of an annular plug 112 force fitted into a passage 113. The mechanism is so arranged that slotted disk 102 initially engages stud 92 locking it in the position shown in FIG. 4 against the urge of spring 106, establishing such position as an initial unarmed position of the rotor. When the slotted disk is rotated to its position shown in FIG. 4A, by rotation of shafts 28 and 38, stud 92 may pass through slot 104 releasing rotor 88 to rotate to its final armed limit stop position shown in FIG. 4A against a surface 114 formed in the housing. The housing and rotor are so arranged to receive an interruptable explosive train including an electrical primer 116 disposed in chamber 118, an elongated

flash detonator 120 fixedly mounted in an aperture 122 extending diametrically through collar 94 of the rotor, and suitable explosive pellets 124, 124 disposed in a passage 126 extending through the housing. An aperture 128 communicates between chamber 118 and bore 100, and an aperture 130 communicates between passage 126 and the bore, apertures 128 and 130 being diametrically disposed through the bore. When the rotor is in the unarmed position flash detonator 120 is out of alignment with apertures 128 and 130 so that even if primer 116 is accidentally ignited the rotor will act as a barrier restricting its output to chamber 118, and when in the armed position flash detonator 120 is in alignment with the aperture so that elements of the explosive train are in alignment whereby ignition of primer 116 will fire detonator 120, as shown by arrow 131, in turn detonating explosive pellets 124, 124, as shown by arrow 131a. Upon detonation, explosive pellets 124, 124 project an explosive charge outward from both ends of passage 126 in the directions of arrow 132, 134 which in turn detonates booster charge 24 and then main charge 26. It is to be noted that the fuse system may be arranged with the booster and final charge disposed either in their full line positions 24, 26, or in the phantom line positions 24a, 26a, adjacent the other end of passage 126, the unused end being left open, as shown, which does not affect detonation of the charge at the other end.

A conventional miniature single pole double throw switch assembly 136 of the type actuatable by an actuating button 138 movable between a retracted position best shown in FIG. 5 and an extended position shown in FIG. 4A and spring urged toward the latter position, is mounted to housing 32 with the actuating button engaged against cam 96. In the unarmed position of FIG. 4, cam 96 locks actuating button 138 in its retracted position actuating a pole 140, shown schematically, into contact with a stationary contact member 142 thereby short circuiting primer leads 144 and 146 through lead 147. In the armed position, FIG. 4A, cam surface 96 permits actuating button 138 to move to its extended position actuating pole member 140 into contact with a stationary contact member 148, electrically connecting primer lead 146 to an output terminal 150 of electric actuator 22 through lead 151, and thereby electrically arming the device, primer lead 144 being electrically connected to the other output terminal 152 through lead 153.

In operation of unit 20, initial acceleration in the direction of arrow 154, FIG. 1, moves weight 76 away from its initial position releasing interlock element 70 and thereby permitting shafts 28 and 38 to start rotating in response to the clockmotor mechanism. If the acceleration is of sufficient level or levels to move weight 76 clear of the path of rotation of interlock element 70 over a sufficient length of time to permit the shaft to rotate from its initial position through an angle in excess of angle θ , the shafts will continue in normal rotation until they reach an angular position whereat stud 92 on rotor 88 passes through slot 104 of slotted disk 102, thereby arming the unit. Since the shafts rotate at a constant rate of rotation determined by the clockmotor mechanism, the time interval between initial acceleration and arming is determined by the angular distance between the initial position of the shafts and their position whereat slotted disk 102 releases the rotor, which in turn is determined by the hereinbefore described preliminary positioning of shaft 38 relative to shaft 28, each of the aforesaid predetermined positions corresponding to a predetermined interval of arming time. Accordingly, the unit may be selectively preset to provide any one of several intervals of time between initial acceleration and arming. If weight 76 is not moved clear of the path of interlock element 70, the shaft will rotate only until interlock element 70 engages the weight thereby preventing further rotation, and upon termination of the acceleration, the weight will return to its initial position in response to the urge of

spring 84 moving interlock element 70 and the shafts back to their initial position against the retarding effect of escapement mechanism 58.

In certain instances, as for example, in multiple propulsion stage missiles, where the missile is subjected to acceleration effects subsequent to initial acceleration, it may be desirable to adapt unit 20 to remain unarmed unless the unit is subjected to acceleration subsequent to the initial acceleration. This may be effected by provision of additional interlocking elements between the rotating shafts and weight 76. For example, an interlock element 156, FIG. 1A, may be fixed to flange 42 and an abutment 158 engageable with element 156 may be affixed to weight 76, the mechanisms being so arranged that interlock element 156 is engageable with abutment 158 unless the unit is subjected to acceleration at a predetermined time subsequent to the initial acceleration.

Obviously many modifications and variations of the present invention are possible in the light of the above teachings. It is therefore to be understood that within the scope of the appended claims the invention may be practiced otherwise than as specifically described.

What is claimed is:

1. An arming device for use in a missile comprising, in combination, first and second shafts adapted for rotation about a common axis, said shafts being positionable in angular position about said axis relative to each other, means for effecting desired adjustment of the angular relationship between said first and second shafts whereby said shafts may be selectively secured together for joint rotation in a plurality of predetermined relative angular positions, a clockmotor mechanism operatively connected to one of said shafts, said clockmotor mechanism being adapted to bias said shafts to rotate in one direction of rotation at a predetermined rate of rotation, acceleration responsive means cooperating with said first shaft adapted to lock said shafts in an initial position whereat said first shaft is in a predetermined angular position about said common axis against said bias of the clockmotor mechanism and adapted to release said shafts in response to acceleration of said housing, arming means actuatable in response to rotation of said shafts from said initial position to a position whereat said second shaft is in a predetermined position about said common axis.

2. A device in accordance with claim 1 wherein one of said shafts comprises a hollow shaft with a central bore extending between its ends and the other of said shafts comprises a shaft journaled in said bore.

3. A device in accordance with claim 1 wherein said means for effecting desired adjustment comprises a first flange fixed to one of said shafts, said first flange having a first aperture formed therein, a second flange fixed to the other of said shafts and disposed adjacent the first flange, said second flange having a series of equiangularly spaced apertures formed therein representing equal increments of time, each of said series of apertures being registerable with said first aperture, and means engageable in said first aperture and one of said series of apertures for securing said flanges together against relative rotation.

4. A device in accordance with claim 1 wherein said acceleration responsive means includes movable means responsive to missile acceleration and engageable with an element carried by said first shaft to interrupt rotation of said shafts unless said initial acceleration of the housing is sustained at a predetermined level of magnitude for a predetermined period of time.

5. A device in accordance with claim 1 wherein said arming means includes an interruptable explosive train, said explosive train including an actuating element adapted to initiate said explosive train, said explosive train including a final explosive element adapted to provide a predetermined explosive output, said explosive train including an interrupter element adapted for movement from an initial unarmed position wherein said interrupter element renders said actuating element ineffective to ini-

tiate said final element to an armed position wherein said actuator element is effective to initiate said final element, movable means to effect movement of said interrupter element to said armed position, and means operatively connecting said second shaft and said movable means to restrain said movable means until said second shaft reaches said predetermined position.

6. A device in accordance with claim 5 wherein said explosive train is operatively responsive to a signal applied thereto through an electrical firing circuit, said interrupter element comprising a rotatable shaft and an associated arming switch connected in said circuit, said armed position being an angular position of said shaft, said shaft and switch being effective to arm the firing circuit, only if the shaft is in said angular position.

7. An arming device to be carried by an accelerated missile comprising first and second co-axial shafts, means for securing said first and second shaft together for joint rotation including adjustable means for manually presetting relative angular positions of said shafts, a clock-work mechanism adapted to bias said shafts to rotate in one direction of rotation and at a predetermined rate, acceleration responsive means cooperating with said first shaft adapted to initially lock said shafts against rotation and to release same in response to acceleration of said missile, a third shaft spring biased in one direction of rotation toward an armed position, means carried by said second shaft engageable with an element carried by said third shaft adapted to permit said third shaft to rotate after said second shaft has rotated to a predetermined position, and arming means carried by said third shaft adapted to move to an armed position when said third shaft is rotated to its armed position.

8. A device in accordance with claim 7 wherein one of said coaxial shafts has an axial bore extending therethrough with the other of said shafts journaled therein.

9. A device in accordance with claim 7 wherein said adjustable means for presetting the angular positions comprises first and second flanges carried by said first and second shafts, and means to selectively fasten said flanges

5

10

in a plurality of predetermined relative angular positions.

10. A device in accordance with claim 7 wherein said acceleration responsive means comprises a weight guidingly supported for rectilinear movement in directions parallel to the direction of missile travel and spring urged toward a locking position wherein it engages an element carried by said first shaft and adapted to move away from said locking position in response to acceleration of said missile.

11. A device in accordance with claim 10 wherein said weight is moved away from said locking position to at least a second position in response to a predetermined magnitude of acceleration, said weight being engageable with said element carried by said first shaft over a predetermined portion of the path of rotation thereof.

12. A device in accordance with claim 7 wherein said means carried by said second shaft is a disk-like element having a face engageable with said element and having formed therein a transverse slot through which said element carried by the third shaft may move when said second shaft is in said predetermined position.

13. A device in accordance with claim 7 wherein said arming means comprises a pyrotechnic train including a pyrotechnic element carried by said third shaft and positionable to complete said train only when the third shaft is in its armed position.

14. A device in accordance with claim 7 wherein said arming means comprises an electric arming switch operatively associated with said third shaft and actuatable to its armed position in response to final movement of said third shaft to its armed position.
